UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

WINDING MACHINE.

Application filed February 26, 1920. Serial No. 361,513.

To all whom it may concern:

Be it known that I, EDWIN N. LIGHTFOOT, a citizen of the United States, residing at New York, in the county of Bronx and 5 State of New York, have invented new and useful Improvements in Winding Machines, of which the following is a specification.

This invention relates to winding machines. Such machines are particularly 10 useful for winding a resistance wire or strip, commonly called a resistor, on a flat insulating core, although not limited to such use.

An object of this invention is to provide 15 an improved winding machine wherein the pitch may be readily and quickly varied during the operation thereof.

Another object is to provide means for presetting a change in pitch whereby the 20 change in pitch may be made quickly during the winding operation.

Another object is to provide improved 25 means for feeding and guiding through the winding head the insulating core upon which the resistor is to be wound.

Another object is to provide improved means for guiding the material to be wound to the core on which it is to be wound.

Another object is to so apply the resistor 30 to the insulating core that both are fully protected against damage.

Other objects and advantages will appear from the specification and claims.

An embodiment of the invention is illustrated in the accompanying drawings.

In the drawings,

Figure 1 is a top plan of the winding machine, parts of the winding head being omitted for the sake of clearness.

Fig. 2 is a vertical section on line 2—2 of Fig. 1;

Fig. 3 is a front elevation of the pitch adjuster;

Fig. 4 is a vertical section on line 4—4 of Fig. 3;

Fig. 5 is a front elevation of the winding head;

Fig. 6 is a horizontal section through the oscillating guide on line 6—6 of Fig. 5;

Fig. 7 is a central vertical section through Fig. 5;

Fig. 8 is an enlarged view of the adjustable core guide shown in Fig. 7;

Fig. 9 is a vertical section on line 9—9 of Fig. 8;

Fig. 10 is a horizontal section on line 10—10 of Fig. 8;

Fig. 11 is a perspective of the adjustable plate and arm of the core guide; and

Fig. 12 is a perspective of the roller carrying arm of the core guide.

The winding machine comprises, in general, a winding head 5 for winding a resistor on an insulating core, a pulling stock 6 for pulling the insulating core through an opening in the winding head and a pitch adjuster 7 for controlling the relative speed of travel of the pulling stock and of rotation of the winding head, whereby the pitch at which the resistor is wound upon the insulating core may be adjusted.

Referring to Figures 1 and 2, the bed plate 15 of the winding machine may rest upon a suitable support such as, for example,

The driving shaft 17 is journaled near each end in supports 18 and 19 depending from the bed plate 15 through openings 20 and 21 in the bench 16. The shaft 17 is provided with a driving pulley 22 by which the winding machine may be driven from any suitable source of power.

A spur gear 23 keyed to the shaft 17 drives the winding head. A bevel gear 24 provided on one end of the shaft 17 meshes with a second bevel gear 25 and through suitable mechanism to be described drives the pulling stock feed screw 26 journaled in brackets 27 and 28 mounted upon the bed plate 15.

The driving shaft 17 and the spur gear 23 and the bevel gear 24 carried thereby and the shaft bearings constitute a unit which is removable so that another unit having different gear ratios may be substituted therefor.

The bevel gear 25 may be fastened by means of a nut 25' and a suitable key to a vertical shaft 30 to the upper end of which may be keyed a friction plate or disk 31. The shaft 30 is journaled in a vertical extension 32' of a removable plate 32 which forms a closure for an opening in the bed plate 15. The plate 32 is fastened to the bed plate 15 by means of screws 33. The shaft 30 is provided with a flange 34 which

rests upon a shoulder on the vertical extension 32' of the plate 32 whereby the shaft is supported.

The friction plate or disk 31 is movable 5 along the shaft 30 and is urged upward by a coil spring 35 surrounding the shaft. One end of the spring 35 rests against the bottom of the friction plate 31 and the other end against a collar 36 surrounding the 10 shaft. The collar 36 rotates with the shaft and is slideable thereon, the shaft being provided with a slot 37 through which extends a pin 38 fastened in the collar 36. The tension of the spring 35 may be varied by means 15 of an adjusting screw 39 extending through a threaded opening in the shaft 30. The pin 38 rests upon the upper end of the adjusting screw 39, which may be locked in adjusted position by a lock nut 39'.

20 A felt washer 40 between the vertical extension 32' of the plate 32 and an annular downwardly extending flange 41 on the friction plate 31 protects the shaft bearing and associated parts from dust, dirt, etc.

25 The friction plate or wheel 31 is provided with a friction surface of suitable material, such as, for example, leather 42.

The plate 32 and the parts carried thereby 30 constitute a unit which may be easily and quickly removed for inspection and repairs by loosening the screws 33. This may be done without disturbing any other part of the winding machine.

35 When the friction plate 31, which is slideable on the shaft 30, becomes badly worn, it may be easily and quickly removed therefrom and replaced by a new plate.

The friction plate 31 drives a wheel 43 of 40 suitable material, such as, for example fibre and is maintained in contact therewith by the spring 35. The fibre wheel 43 is secured to a sleeve 44 by means of a nut 45 and may therefore be readily removed and replaced by another wheel when desired.

45 The sleeve 44 is journalled in a bracket 46 mounted upon the bed plate 15 and is keyed to a shaft 47 journalled in the bracket 27. The outer end of the shaft 47 is provided with a spur gear 48 meshing with a spur gear 49 on the end of the feed screw 26.

The sleeve 44 is provided with two flanges 50 and 51. In the groove thus formed between the two flanges, there is a split collar 52 carrying oppositely positioned laterally 55 extending pins 53 and 54. (See Figs. 3 and 4.) The pin 53 works in the slot of a guide 55 carried by the arm 56 of a fork pivoted on a spindle 57 which may be supported in a frame 58 secured to the bed plate 15. The 60 other pin 54 works in the slot of a similar guide 59 carried by the other arm 60 of the pivoted fork.

The front arm 56 of the fork is provided with a handle 61 by which the fork may be 65 moved about its pivot to slide longitudinally

the sleeve 44 on the shaft 47. When the sleeve 44 is moved to the right, the fibre wheel 43 is moved nearer the center of the friction plate 31 whereby the speed of the sleeve is reduced. In this way the speed of 70 rotation of the pulling stock feed screw 26 may be varied to control the pitch of the resistor being wound upon the insulating core.

The front arm 56 also carries a pointer 62 which cooperates with a scale 63 provided 75 on the plate 64, whereby the winding machine may be easily and quickly adjusted for the desired winding pitch.

In order that the pitch adjuster may be locked when set for the desired pitch, a 80 screw 65 extends through an arcuate slot 66 in the plate 64 and through an alined opening in the arm 56 and into a threaded opening in the inner end of the handle 61. The screw 65 has a head 67. When setting the 85 winding machine for the desired pitch, the fork is moved by the handle 61 until the pointer 62 is opposite the designation on the scale 63 which indicates the desired pitch. The fork may then be locked in this 90 position by turning the handle 61 to tighten the screw 65 thus locking the plate 64 and the arm 56 between the head 67 of the screw and the inner end of the handle 61.

In some classes of apparatus in which 95 heating elements are used, it is desirable that some portion or portions of the heating unit develop greater heat than other portions. Where the heating element employed 100 comprises a relatively long insulating core upon which the resistor is wound, the heating element may be arranged to develop different degrees of heat in different portions thereof by winding the resistor with different numbers of turns per unit length. Different 105 numbers of turns per unit length are obtained by varying the pitch at which the resistor is wound. The present winding machine is arranged to wind a resistor with from approximately two and three-quarters 110 to seventy-two turns per inch.

The pitch adjuster of the winding machine is arranged so that it may be preset for two different pitches whereby the pitch 115 may be easily and quickly changed from one to the other during the winding operation. To this end two adjustable stop screws 68 and 69 are positioned on opposite sides of the arm 56. These adjustable screws are held in threaded lugs 70 and 71 provided on the face of the plate 64. Lock nuts 72 and 73 are provided for holding the screws 68 and 69 in adjusted position.

Before starting to wind the resistor on 120 the insulating core, the arm 56 may be moved until the pointer 62 indicates one of the desired pitches on the scale 63. One of the stop screws 68 or 69 is then adjusted until its inner end engages one side of the 125 arm 56. The pitch adjuster may then be 130

- 5 preset for the other of the desired pitches by moving the arm 56 until the pointer 62 indicates the pitch on the scale 63. The other stop screw may then be adjusted until 5 its inner end engages the side of the arm 56.
- 10 When the proper length of the insulating core has been wound with the resistor at the desired pitch, the machine may be quickly changed to wind at the other preset 10 pitch. This may be accomplished by grasping the handle 61 and quickly moving the arm 56 until it rests against the end of the other adjustable stop screw.
- 15 Other spur gears mounted upon studs journalled in bearings 74 and 75 may be provided for changing the ratio of speed between the pulling stock feed screw 26 and the shaft 47. These spur gears would mesh with each other and with spur gears of suitable size on the shaft 47 and the feed screw 26. Motion would then be transmitted from the spur gear on the shaft 47, through the gears journalled in the bearings 75 and 74 to the gear on the feed screw 26.
- 20 25 The spur gears and the associated thumb nuts 48' and 49' are protected by a casing 76 fastened to the bracket 27 by means of wing bolts 77.
- 30 A dovetail track or slide comprising angle rails 78 and 79 and overhanging cover strips 80 and 81 rests upon and is suitably secured to the brackets 27 and 28. (See Figures 1, 2, 3 and 4.)
- 35 Figures 1 and 2 show the pulling stock which comprises a base 85 which rests upon and is adapted to slide along the rails 78 and 79 of the track, and an upright 86 which may be formed integrally with the base 85 or otherwise suitably secured thereto.
- 40 45 The pulling stock is operatively connected with the feed screw 26 by means of a half nut 87. The half nut 87 is normally maintained in engagement with the feed screw 26 by a coiled spring 88 seated in a recess in the base 85 and resting against the half nut 87.
- 50 55 The half nut 87 may be moved out of engagement with the feed screw 26. To this end, a rod 89, whose lower end is connected with the half nut 87, is pivotally connected with a lever 90 fulcrumed in the upper end of a pin 91 which may be screwed into the base 85. The lever 90 is provided with a handle 92 for moving the lever 90 on its fulcrum and thereby raising the half nut out of engagement with the feed screw 26. The pulling stock may then be moved readily along the track to any desired position thereon.
- 60 65 The engagement and disengagement of the half nut 87 with the feed screw 26 may be controlled independently of the handle 92. For this purpose, there is provided a cam ring 93 to which is attached a handle 94. As shown in Figs. 1 and 2, the half nut 87 and the feed screw 26 are out of engagement. By turning the handle 94 either to the right or to the left from the central position shown, allows the lever 90 to rest upon a lower surface of the cam ring 93, and the 70 spring 88 forces the half nut 87 into engagement with the feed screw 26. To elevate the half nut 87, the handle 94 is moved back into its central position thereby elevating the right hand end of the lever 90, 75 which carries with it the connected rod 89 and half nut 87—against the force of the spring 88.
- 80 85 The pulling stock is provided with a pair of clamping jaws 95 and 96 for gripping the insulating core upon which the resistor or resistance wire or strip is to be wound. These clamping jaws 95 and 96, the former of which is pivoted at its rear end to the jaw 96, may be held in clamping position 85 against the action of spring 97 by means of a clamping screw 98 carried by a bracket 99 which is secured to the lower clamping jaw 95.
- 90 95 The clamping jaw 95 may be formed integrally with or otherwise suitably attached to a cross head 100 which is adapted to be moved transverse to the direction of travel of the pulling stock. This cross head 100 moves between guide rails 101 and 102 95 suitably secured to the front face of the upright 86. The cross head 100 may be locked in adjusted position by means of a clamping screw 103.
- 100 105 The pulling stock carries a pointer 104 which moves over a scale 105 provided on the cover strip 80. By means of the pointer and scale the operator of the winding may readily determine when the proper amount of the resistor has been wound upon the insulating core. The pointer and scale are also very useful for indicating to the operator when to shift the pitch adjusted to change from one to the other of the preset pitches.
- 110 115 When winding the resistor upon curved insulating cores, and in order that the resistor may be wound evenly thereon, it is desirable that the curved insulating core be moved through the winding head along a line approximating the axis of curvature of the insulating core. This may be accomplished by causing the cross head 100 and the clamping jaws 95 and 96 to move transverse to the line of travel of the pulling stock while the pulling stock is moving along said line of travel.
- 120 125 130 A bracket 105 therefore may be suitably secured to the track rail 79 by means of bolts or screws 106. A removable adjustable cam 107 may be maintained by the arms of the bracket 105 in spaced relation to the pulling stock and in approximately the same horizontal plane with a roller 108 on one end of a splined shaft 109 carried by the cross head 130

100. The particular form of the cam 107 employed depends upon the curvature of the insulating core upon which the resistor is to be wound.

5 When setting the winding machine for winding the resistor upon curved insulating cores, the pulling stock is moved into the position shown in Figs. 1 and 2. The handle 94 may then be moved to the right 10 or left to permit the half nut 87 to mesh with the feed screw 26. The splined shaft 109 may be moved into a position with the roller 108 engaging the cam 107. The splined shaft 109 may then be locked to the 15 cross head 100 by means of the clamping screw 110. The clamping screw 103 is loosened to unlock the cross head 100.

20 During the operation of winding the resistor upon curved insulating cores or strips and as the pulling stock is moved to the left the roller 108 moves along the cam 107. The cross head 100 with the associated clamping jaws 95 and 96 is therefore gradually moved 25 transverse to the line of travel of the pulling stock. This transverse movement is against the action of a spring 111 one end of which is secured to a pin 112 carried by the guide rail 101, and the other end of which is secured to a pin 113 carried by the 30 cross head 100. This spring 111 maintains the roller 108 against the cam 107.

35 The winding head comprises, in general, an adjustable guide for guiding the insulating core therethrough, a spool for holding a supply of the resistor and apparatus for guiding the resistor from the spool and for applying the resistor to the insulating core.

40 The assembly of the winding head is shown in Figs. 1 and 2. Figs. 5 to 12 inclusive show the details of the winding head.

45 The winding head, part of which is stationary and part rotatable is supported by a bracket 114 mounted upon and suitably secured to the bed plate 15 by means of bolts 115. The bracket 114 is provided with a circular opening in which is supported a hollow stationary bearing member 116. This bearing member 116 is locked to the bracket 114 by means of a key 117 and a 50 nut 118.

55 The rotatable parts of the winding head are driven by a gear 119 which revolves on the bearing member 116. This gear 119 is driven from gear 23 on the drive shaft 17 through an idler gear 120 mounted on a stud 121 secured to the bracket 114. A hand wheel 122 by which the operator may positively control the winding operation may be formed integrally with the gear 119 or otherwise suitably secured thereto as by bolts 123.

60 A removable spool 124 for holding the resistor is mounted upon the hub 125 of the gear 119. To permit the spool 124 to revolve freely it rests upon rollers 126 and

against rollers 127 supported by the hub 125.

The gear hub 125 and the spool 124 are held in proper position on the bearing member 116 by upper and lower disk parts 128 70 and 129 resting in a groove 130 in the bearing member 116 and suitably detachably secured thereto by thumb screws 131.

The speed of the spool 124 may be controlled by an adjustable brake mounted on 75 the lower disk 129. This brake comprises a spring 132 of suitable material carried by the inner end of a pusher rod 133. This pusher rod 133 extends through a thumb screw 134 threaded into a boss 135 on the disk 129. The inner end of the thumb screw 134 engages the spring 132. By turning the thumb screw 134, the tension of the brake spring 132 may be adjusted. When proper adjustment of the brake spring 132 has been secured the thumb screw 134 may be locked in adjusted position by the lock nut 136. Greater pressure of the brake spring 132 on the spool 124 may be secured temporarily 80 by pushing on the rod 133.

85 The upper disk 128 carries a radially adjustable plate 137 adapted to be moved between guide rails 138 and 139 and to be locked in adjusted position by a clamping screw 140 provided with a handle 141 for operating 90 the same.

95 The adjustable plate 137 is provided with a boss 142 in which an oscillating head 143 is suitably supported and journalled by means 100 of the ball bearings 144 and 145. A cover 146 protects the ball bearings from dirt, dust, etc. The oscillating head 143 is provided with an opening in which a guide tube 147 for the resistor is locked by a pin 148 entering a recess in one side thereof. This pin 148 is secured to a spring 149 attached to the oscillating head. A coil spring 150 surrounding the boss 142 and having its ends entering openings in the boss 142 and the head 143 centers the head 143, and normally maintains the guide tube 147 in radial alinement 110 but permits oscillation thereof during the winding operation. The guide tube 147, as shown in Fig. 6, is provided with two recesses 147^a and 147^b located 180° apart and with either of which the pin 148 may cooperate to maintain the guide tube in either of 115 two positions with respect to the head 143.

120 Figures 8 to 12 showing the details of the mechanism for guiding the insulating core through the winding head will now be described.

125 The insulating core is drawn by the pulling stock 6 between two rollers 151 and 152 provided with flanges 151' and 152' against which the edges of the flat insulating core may rest as it is being drawn between the rollers. The rollers 151 and 152 are positioned in openings provided in the respective arms 153 and 154 and are carried by 130

suitable pins passing therethrough. The arms 153 and 154 at their rear ends are keyed to the respective shafts 155 and 156 and rotate therewith but are longitudinally slide-

5 ble thereon, so that the rollers may be adjusted to and from the center. The shafts 155 and 156 are journalled in opposite sides of a rectangular frame 157 seated in a rectangular opening in the bearing member 116.

10 The rollers 151 and 152 are normally urged toward each other by two springs 158 and 159. One end of the spring 158 is seated in a recess in the arm 154 and the other end in a recess in a rearwardly extending arm 160 formed integrally with or otherwise suitably secured to the angle plate 162. Similarly, one end of the spring 159 is seated in a recess in the arm 153 and the other end in a recess in a rearwardly extending arm 161 formed integrally with or otherwise suitably secured to the angle plate 163.

15 The arms 160 and 161 at their rear ends are forked, and openings are provided in the forks whereby the arms may be supported by the respective rocking shafts 156 and 155. The openings in the forks are large enough to clear the shaft and its associated key, so that the arms 160 and 161 are not affected by the rocking movement of the

20 shafts 155 and 156. When the arms 154 and 160 are assembled on the shaft 156, the hub 154' of the arm 154 is positioned between the forks of the arm 160, so that the transverse position of the arm 154 may be varied by movement of the arm 160. Similarly, when the arms 153 and 161 are assembled on the shaft 155, the hub 153' of the arm 153 is positioned between the forks of the arm 161, so that the transverse position of the arm 153 may be varied by movement of the arm 161.

25 The angle plates 162 and 163 are seated at their upper end in a slot 166 and at their lower end in a slot 167, the slots being provided in the front face of the bearing member 116. Retaining plates 168 and 169 attached to the front face of the retaining plates are provided for the upper and lower ends of the angle plates 162 and 163. The angle 30 plates 162 and 163 are thus definitely positioned whereby the rearwardly extending arms thereof are firmly supported.

35 In order that the rollers 151 and 152 may be moved to and from the center to accommodate different widths of insulating core, the angle plates 162 and 163 and associated arms are arranged to be moved transversely to the bearing member 116. To this end, right and left hand screws 170 and 171 positioned in transverse openings in the bearing member 116 have threaded engagement with the respective arms 160 and 161. The two screws 170 and 171 may be suitably connected, so that they may be operated 40 simultaneously to cause the simultaneous

movement of the angle plates and associated arms and consequently the simultaneous movement of the rollers 151 and 152 to or from the center.

45 In order that the insulating core may be held firmly and in order to protect the edges thereof while the resistor is being wound thereon, the insulating core after leaving the rollers 151 and 152 is drawn between two angle strips 172 and 173. The angle strip 172 is attached to a vertical extension of the arm 154 and the angle strip 173 to a vertical extension of the arm 153.

50 As previously explained, the springs 158 and 159 urge the arms 153 and 154 toward each other, so that the insulating core, as it is being drawn through the winding head, is firmly engaged by the rollers 151 and 152 and by the strips 172 and 173. While the arms 153 and 154 are keyed to the rocker 55 shafts 155 and 156, there is sufficient play to prevent interfering with the action of the springs 158 and 159.

55 Before starting the winding operation, it is desirable that the insulating strip or core be properly positioned in the core guiding mechanism of the winding head. In order that the arms 153 and 154 and parts carried thereby may be forced apart against the action of the springs 158 and 159, a pair of 60 levers 174 and 175 are provided. The lever 174 is keyed and locked to the rocker shaft 156 and the lever 175 to the rocker shaft 155. The free ends of the levers 174 and 175 rest upon the inner surface of a cam ring 176 65 which is seated in a circular opening within the hollow bearing member 116. The inner end of a funnel shaped ring 177 is attached to the cam ring 176, so that by rocking the ring 177 about its axis by means of the protecting handles 178, the cam 176 causes the levers 174 and 175 to rock the shafts 155 and 156. The rollers 151 and 152 and the angle strips 172 and 173 are thus separated to permit the positioning of the insulating 70 core therebetween. After the insulating core has been positioned, the parts of the guiding mechanism may be restored to their normal position by rocking the funnel shaped ring 177 in the opposite direction.

75 The cam ring 176 and the funnel shaped ring 177 may be maintained in position by screws 179 passing through slots in the ring 177 and having engagement with the bearing member 116. The screws 179 and cooperating slots also serve to limit the oscillatory movement of the two rings.

80 By providing the funnel shaped opening in the bearing member 116, the core guiding mechanism is readily accessible from the rear. Consequently, it is possible to position in the winding head, very short lengths of insulating cores which are required in some classes of electrically heated apparatus.

The winding head as constructed is a unit which may be readily removed from the bracket 114 after first removing the gear 120 and the nut 118.

5 By taking out the thumb screws 131, the disks 128 and 129 may be readily removed from the winding head. The spool 124, if empty, may then be removed and replaced by one containing a supply of resistor.

10 In order that the resistor 180 may be properly guided from the spool 124 into the guide tube 147, the resistor 180 first passes between a pair of flanged rollers 181, then between a pair of flanged rollers 182 and 15 finally over a flanged roller 183 directly into the opening through the guide tube 147.

The pair of guide rollers 181 are carried by an arm 184 supported from a bracket 185. The bracket 185 is formed integrally with or is otherwise suitably attached to the disk 128 and extends radially therefrom.

The pair of guide rollers 182 are carried by an arm 186 adjustably secured to the disk 128 and a bracket 187 by means of 25 screws or bolts 188 and 189. The bracket 187 is secured to and supported by the disk 128 at the top of the guide rails 138 and 139. The guide roller 183 is supported on a pin 190 fastened in the bracket 187.

30 A protecting cover 191 is provided for all moving parts of the winding head except the handwheel 122 which is left exposed so that it is readily accessible to the operator for positively controlling the winding of the resistor on the insulating core. The cover 191 is made of two parts, the upper of which is hinged to the lower so that it may be easily opened. The front face of the core is provided with a central opening through 35 which the insulating core with the resistor wound thereon may be drawn from the winding head by the pulling stock.

The resistor 180 enters the opening in the guide tube 147 at the dead center thereof 45 so that the oscillatory movement of the guide tube during the winding operation does not subject the resistor to any unnecessary bending between the guide roller 183 and the point of entry into the guide tube 147.

During the winding operation, the angle strip 172 is immediately above the insulating core and has an edge thereof in alignment with one edge of the insulating core, 55 while the other angle strip is similarly positioned below the insulating core but at the other edge thereof.

The resistor 180 passes directly from the lower end of the guide tube 147 onto the 60 angle strips 172 and 173 and the insulating core positioned therebetween. These angle strips 172 and 173 therefore protect the edges of the insulating core during the winding operation, and eliminate or greatly reduce the breaking of the insulating core at 65

its edges. When it is understood that the insulating core usually is a flat strip of mica, the importance of protecting the edges thereof will be appreciated. Furthermore, during the winding operation, the guide tube 147 in its oscillations follows very closely the outer edges of the insulating core, thereby maintaining a minimum distance between the outlet end of the guide tube 147 and the insulating core, and winding the resistor thereon evenly and with uniform tension.

70 Since the plate 137 carrying the guide tube 147 is radially adjustable, the guide tube 147 may be positioned so that the very best possible results may be obtained with insulating cores of different widths.

80 The thumb screw 134 of the spring brake may be tightened up sufficiently to lock the spool 124 to the gear hub 125, when, if desired, the spool may be refilled with resistance wire without removing the spool from the winding head.

85 What is claimed is:

1. In a winding machine, the combination 90 with a rotatable member and a support for material to be wound carried by said member, of a core member of angular cross section about which said material is adapted to be wound, guiding means for said material including means enabling shifting of the direction of travel of said material out of radial alignment with respect to the center of said core member to thereby maintain a minimum distance between the outlet end 95 of said guiding means and the surface of said core.

100 2. A winding machine comprising a rotatable head, a rotatable support for the material to be wound carried by the head, and means for guiding the material from the support to a core on which it to be wound, said means including a radially adjustable member carried by the head and a guide pivotally mounted on said member.

105 3. In a winding machine, the combination 110 with a rotatable head member and a support for material to be wound carried by said member, of guiding means for the material including means enabling shifting of the direction of travel of the material being wound in a manner to minimize variations in the distance between said guiding means and the material immediately after winding thereof.

115 4. In a winding machine, the combination 120 with a rotatable head member and a support for material to be wound carried by said member, of guiding means for the material including means for maintaining a relatively large angle between the material immediately before winding and the material immediately after winding under conditions of variation in radius of the wound body of material.

5. A machine for winding a conductor on an insulating core, having in combination, a rotatable head having an opening, means for moving the core through the opening, a rotatable spool for the conductor supported by the head, a radially adjustable bracket carried by the head, and means for guiding the conductor from the spool to the core and including a guide pivotally mounted on the bracket.

6. In a winding machine, in combination, a winding head having a rotatable member adapted to carry the material to be wound and a stationary member including positioning and guiding means for a core on which the material is to be wound, and means for guiding the material from the rotatable member to the core pivotally mounted on the rotatable member.

7. In a winding machine, the combination with a rotatable member and a support for material to be wound carried by said member, of winding means for the material including means for maintaining substantially a constant angle between the material immediately before winding and the material immediately after winding, during shifting of the region of junction between such wound and unwound material with reference to the axis of rotation of said head member.

8. In a winding machine, the combination with a rotatable head member and a support for material to be wound carried by said member, of guiding means for the material including means to be actuated by the material being wound for varying the direction of travel of the latter in response to shifting of the region of junction between the wound and the unwound material with reference to the axis of rotation of said head member, to thereby maintain substantially a constant and relatively obtuse angle between the material immediately before winding and the material immediately after winding.

9. In a winding head for a winding machine having in combination a stationary member with an opening therein, a rotatable supporting member for the material to be wound, means for moving through the opening a core on which the material is to be wound, adjustable core guiding and positioning means located within the opening, and means for guiding the material from the rotatable supporting member to the core pivotally supported by the rotatable member.

10. In a winding head for a winding machine having in combination a stationary member with an opening therein, a rotatable member supported by the stationary member, a supporting spool for the material to be wound carried by the rotatable member, guiding and positioning means for a core

on which the material is to be wound supported within the opening, and means for guiding the material from the spool to the core pivotally supported by the rotatable member.

11. In a winding head for a winding machine, in combination, a stationary member having an opening therein, a rotatable supporting member for the material to be wound, guiding rollers for a core on which the material is to be wound supported within the opening, and means for guiding the material from the rotatable member to the core pivotally supported by the rotatable member.

12. A winding head for a winding machine comprising a stationary member with an opening therein, a rotatable supporting member adapted for the material to be wound mounted on the stationary member, adjustable arms supported within the opening, guide rollers for a core on which the material is to be wound carried by the arms, and means for guiding the material from the rotatable member to the core.

13. A winding head for applying material to a core comprising a stationary member having an opening therein, a rotatable material supporting member mounted on the stationary member, core guiding and positioning members located within the opening, a pair of core protecting fingers supported by and projecting from the guiding and positioning members, and means for guiding the material from the rotatable supporting member over the protecting fingers and onto the core, said guiding means being pivotally supported by the rotatable member.

14. In a winding machine for applying material to a core, the combination of a rotatable material supporting head core, guiding and positioning members, core protecting fingers supported by said members, and means for guiding the material from the rotatable head over the protecting fingers and onto the core.

15. In a winding machine, the combination of a rotatable head adapted to carry the material to be wound, guiding and positioning members for a core on which the material is to be wound, core protecting fingers supported by said members, and means for guiding the material from the rotatable head over the protecting fingers and onto the core and including a guide pivotally supported by the rotatable head.

16. In a winding machine for applying material to a core, the combination of a rotatable material supporting head having an opening through which the core is adapted to extend, a pair of brackets extending into the opening, rollers rotatably mounted in the brackets, core protecting fingers fastened to the brackets and co-operating with

the rollers to position and guide the core, and means for guiding the material from the rotatable head over the protecting fingers and onto the core.

- 5 17. In a winding machine, the combination of a rotatable head adapted to carry the material to be wound and having an opening through which a core is adapted to extend, a pair of adjustable arms, rollers for 50
10 guiding and positioning the core carried by the arms, core protecting fingers carried by the arms, and means for guiding the material from the rotatable head over the protecting fingers and onto the core. 55
15 18. In a winding machine for applying material to a core, the combination of a rotatable material supporting head having an opening therein, means for feeding the core through the opening, means for guiding the 60
20 material from the rotatable head onto the core and including a guide finger pivotally mounted on the head to swing in a plane at an angle to the axis of rotation of the head, means for determining the pitch at which 65
25 the material is wound on the core, and means for changing the pitch during the operation of the machine. 70
19. In a winding machine, the combination with a winding head having a rotative 75
30 member to supply and apply the winding material to and about a non-rotative core, of means for so moving the core that the rate of such movement is a measure of the winding pitch and means providing for pre- 80
35 selecting, during winding, different speeds of movement of the core and also for enacting the speed changes so preselected to thereby both preselect and effect changes in pitch during the winding operation. 85
40 20. In a machine for winding material upon a moving core, the combination with a winding head having a rotative member to carry and apply the material to the core at a predetermined pitch, of means for pre- 90
45 setting the machine, while winding at a given pitch, to wind at a different pitch and

for thereafter causing the machine to wind at the pitch so preselected.

21. In a machine for winding material on a core, the combination of a rotatable head adapted to carry and apply the material to the core; means for moving the core in a plane transverse to the plane of rotation of the head and at a predetermined rate, said means including a driving disk and a 50
55 driven disk whose periphery is in functional engagement with the face of the driving disk, and means for varying the position of the driven disk on the driving disk to change the rate of movement of the core during the 60 winding operation.

22. In a machine for winding material upon a core, the combination with a rotative head member adapted to carry the material, a driving shaft, means for driving said head member from said shaft and a pulling stock for drawing the core through an opening in said head member at a rate which is a measure of the winding pitch of an adjustable driving connection between said driving 70
75 shaft and said pulling stock and control means for said driving connection providing for presetting a desired drive ratio during operation of the drive at a different ratio. 80

23. In a machine for winding a conductor on an insulating core, a rotatable head having an opening through which the insulating core passes, a support for the conductor carried by the head, a driving shaft, means for driving the head from the shaft, a pair 85
85 of clamping jaws for gripping the insulating core, a guide for the clamping jaws, means driven by the shaft and cooperating with the guide to move the clamping jaws in a plane transverse to the plane of rotation of the head, and means operable during the winding operation for changing the rate of movement of the clamping jaws so as to change the winding pitch.

In witness whereof, I have hereunto subscribed my name.

EDWIN N. LIGHTFOOT.
